UNITED STATES PATENT OFFICE.

PATRICK FRANCIS CONNOR, OF NEW YORK, N. Y., ASSIGNOR OF ONE-FOURTH TO ORIN W. WARD AND ONE-EIGHTH TO AGNES SCHULL-GRAMM, BOTH OF NEW YORK, N. Y., AND ONE-EIGHTH TO EDGAR C. ABBOTT, OF BOSTON, MASSACHUSETTS.

DRILL-PRESS.

1,155,891.

Specification of Letters Patent.

Patented Oct. 5, 1915.

Application filed December 31, 1914. Serial No. 879,897.

To all whom it may concern:

Be it known that I, PATRICK FRANCIS CONNOR, a citizen of the United States, and a resident of the city of New York, borough of Manhattan, in the county and State of New York, have invented a new and Improved Drill-Press, of which the following is a full, clear, and exact description.

This invention relates to metal working tools and has particular reference to boring and drilling devices.

Among the objects of the invention is to provide a drill press adapted for practically universal employment or one which the mechanician may carry with him readily and apply to practically every type of work. In other words, the device constituting the subject matter of this invention comprises a bracket which may be held in any desired position upon a fixed support or may be clamped to the bar, rod, plate or other job to be bored.

The foregoing and other objects of the invention will hereinafter be more fully described and claimed and illustrated in the drawings forming a part of this specification in which like characters of reference indicate corresponding parts in all the views, and in which—

Figure 1 is a side elevation of a preferred embodiment of the invention, the same being shown supported upon a fixed support as above a bench; Figs. 2 and 3 are horizontal sections on the corresponding lines of Fig. 1; Fig. 4 is a vertical transverse sectional detail on the line 4—4 of Fig. 1; Fig. 5 is a bottom plan view of the foot piece and bed plate of Fig. 1; Fig. 6 is a side elevation showing the drill press supported upon the end of a rod or post to be drilled; Fig. 7 is a horizontal section on the line 7—7 of Fig. 6; Fig. 8 is another modification showing the use of the machine clamped to a pipe and so held for operation thereon; Figs. 9 and 10 are side and plan views indicating the device acting upon a horizontal angle bar, the main bracket being supported in a horizontal position on a bench; Figs. 11 and 12 are views showing the application of the

device to a flat bar, the bar constituting the means for supporting the drill press; and Fig. 13 is a view corresponding to Fig. 2 but showing a modified form of stem adapted to support the shank when turned at right angles in either direction from the position shown in Fig. 1.

The several parts of this device may be made of any suitable materials, and the relative sizes and proportions, as well as the general design of the mechanism, may be varied within the scope of the claim without departing from the spirit of the invention hereinafter more fully described and specifically claimed.

Referring more particularly to the drawings, I show a bracket 15 comprising two parallel bars 15^a and 15^b to and between which are secured a head piece 16 and a foot piece 17. The head is adjustable lengthwise of the bracket by means of bolts 18 acting through any suitable number of holes 19 at the upper ends of the bracket bars. The head at its free end is provided with a hub 20 through which a feed screw 21 is operated toward and from the foot piece by a suitable means such as a hand wheel 22. The foot piece is provided preferably with a pair of parallel prongs or toes 23 which extend upon opposite sides of the vertical plane of the feed screw and main portion of the bracket.

At 24 I show the main part or shank of the drill mechanism *per se*, this part of the mechanism resembling in general a well known type of breast drill, and including a master gear 25 journaled upon a stud 26 extending laterally from the shank, said master gear meshing with an idle pinion 27 and another pinion 28 which drives the chuck 29 and drill bit 30. In all adaptations of the device, however, the operator is relieved from holding the drill mechanism, the same being supported in the bracket, and the shank is directly guided or supported in the plane of the bracket aforesaid by means of a rigid stem 31 shown in Fig. 1 as tapped directly through a hole 32 in the shank just above the stud 26, and at its other end the stem is clamped to a slide or block 33 by

means of a thumb nut 34 and a shoulder 35. The slide 33 is adapted to move freely longitudinally of and between the bars 15^a and 15^b, but is held from lateral displacement or 5 tilting by means of projections or flanges 33' at the corners thereof as shown best in Fig. 2.

In Figs. 1 and 5 I show a bed plate 36 having a flat face and of any suitable outline, the same being adapted to be slipped 10 into place upon the prongs 23 of the foot, keepers 37 being connected to the bottom of the bed plate carrying set screws 38 for clamping the bed plate in proper position 15 on said foot. The bed plate has a central opening 39 toward and through which the tool 30 is directed and through which a peculiar form of clamping block 40 may be passed. This block includes a finger 41 having 20 one end extending forwardly after passing downwardly through the opening 39 far enough to allow the rear end to pass through and beneath the opening, whereby when the block is then moved rearwardly the shorter 25 end will interlock beneath the plate as indicated in Figs. 3 and 5. A pin or screw 42 may then be used to hold the block in place. Said block on its uppermost portion has a lip 43 overlapping the bar B to be drilled. 30 The bracket and drill proper may be connected to some rigid support such as indicated at 44 by means of connectors 45 as shown in Fig. 1, or it may be held in a horizontal position by the use of the same connectors as indicated in Fig. 9. Instead, 35 however, of connecting the bracket to some fixed stationary support, I provide means whereby the bracket may be clamped temporarily, but rigidly, for practical purposes 40 to a post, rod, bar or the like to be treated. In Figs. 6 and 7 I show, for example, a vertical metal post P, the end of which is to be bored as for applying an ornament thereto, said post being straddled by the prongs 23. 45 For this purpose I show a clamp having jaws 46 and 47 having aligned holes through which the prongs 23 extend. A pair of bolts 48 are pivoted at 49 to the block 46, and after the block 47 is slipped into position against the side of the post opposite the block 46, said bolts 48 are swung downwardly into and through slots 48' formed in the upper portion of the block 47 and are then tightened by thumb nuts 50. The 55 bracket 15 and feed mechanism being the same as before described, the machine will now be in position to drill the hole desired.

In Fig. 8 the same bracket and foot members are shown clamped by means of a 60 clamping block 51 to the pipe P' through which a transverse hole is to be drilled. The block 51 has a plurality of holes through which prongs 23 project and it is

locked to the pipe by means of a serrated jaw 52 acted upon by set screws 53 passing 65 through a yoke 54 interlocking with the sides of the block 51. The tool 30 (not shown in this figure) will be understood as operating downwardly at one side of the yoke 54 and block 52. 70

At A, Figs. 9 and 10, I show an angle bar, one flange of which is to be drilled. At 55 is shown a clamp slipped upon the prongs 23 as already described. This clamp includes a pair of dogs 56 pivoted at 57 to the 75 upper portion of the block 55 and adapted to be turned down upon the opposite side of the angle bar from the block 55, said dogs carrying set screws 58 which act through the dogs against the angle bar to be drilled. 80 Said dogs are held temporarily in position by a pair of keepers 59 pivoted at 60 to the upper part of the block.

In Figs. 11 and 12 I show a bar B' of larger dimensions than the first mentioned 85 bar and adapted by means of a clamp to support the machine while in use. This clamp comprises a plate 61 connected by a bolt 62 to the foot piece 17 through an anchor block 63 close to the bar. The gripping effect is completed by means of a set screw 64 acting close to the end of the plate 61 which spans or straddles the bracket 15 whereby the clamp plate 61 is held steady. The free end of the plate 61 is provided 95 with fingers 61' which span the point where the hole is to be drilled. The anchor plate 63 is locked temporarily to the edges of the prongs 23 by screws 65.

As shown in Fig. 1, the master gear 25 100 operates in a plane transverse to the plane of the bracket and stem 31. For certain purposes it is necessary or desirable for the drill proper to be turned to the right or left from said position through an angle of 105 90 degrees whereby the wheel 25 will operate in a plane parallel to the bracket and stem. For this purpose, as shown in Fig. 13, I provide a stem 31' having a socket 31^a at its free end which embraces the tapped 110 portion of the shank 24 and it is connected rigidly to the shank by means of a screw 31^b which passes into the hole 32 of the shank. The other end of the stem is connected, as above described, to the slide 33 115 for operation along the bracket 15.

I claim:

In a drill press of the character set forth, the combination of a bracket, head and foot members connected to the opposite ends of 120 the bracket, work holding means connected to the foot, feed means acting through the head toward the foot, drill mechanism between the head and the foot and including a shank against which the feed means operates, said shank having a tapped hole per- 125

pendicular to its axis, a stem having at one end a socket embracing the tapped portion of the shank, a screw passing through the socket into said hole, whereby the drill mechanism may be operated on either side of the vertical plane of the stem, and a slide movable along the bracket and connected to the end of the stem opposite the shank.

In testimony whereof I have signed my name to this specification in the presence of 10 two subscribing witnesses.

PATRICK FRANCIS CONNOR.
